GEORGE SMAJDA, OF EAST ST. LOUIS, ILLINOIS.

RAIL-FASTENING DEVICE OR CLAMP.

1,190,577.

Specification of Letters Patent.

Patented July 11, 1916.

Application filed November 22, 1915. Serial No. 62,818.

To all whom it may concern:

Be it known that I, FEKECS PÁL, a subject of Francis Joseph, Emperor of Austria and Apostolic King of Hungary, residing 5 at East St. Louis, county of St. Clair, State of Illinois, have invented a certain new and useful Rail-Fastening Device or Clamp, of which the following is a specification, reference being had to the accompanying drawing, forming a part thereof.

This invention relates to a certain new and useful rail-fastening device or clamp, the principal object of my present invention being to provide a simple, strong, durable, 15 and comparatively inexpensive device which may be readily manufactured and which may be easily and conveniently operatively engaged both with a railroad-tie and rail for rigidly fastening or clamping the rail 20 to and upon the tie.

With the above and other objects in view, my present invention resides in certain novel features of form, construction, arrangement, and combination of parts, all as will herein- 25 after be described and afterward pointed out in the claims.

In the accompanying drawing, which shows my invention in preferred form, Figure 1 is a side elevational view of a railroad-tie, showing in end elevation rails operatively fastened or clamped thereupon by a set or pair of my new clamping or fastening devices; Fig. 2 is a plan view of a plurality of railroad-ties and of rail-clamping 35 or fastening members embodying my invention in operative engagement therewith, one rail, with its companion rail omitted, being shown, partly broken away and in section, operatively fastened to the ties by 40 my clamping devices and one of the ties being also shown partly broken away and in section; Fig. 3 is an end view of a railroad-tie, showing a rail in side elevation operatively fastened or clamped thereupon 45 by a clamping or fastening device embodying my invention; and Fig. 4 is a perspective view of one of the coöperating members forming part of my new rail-fastening device or clamp.

Referring to the said drawing, in which like reference characters refer to like parts throughout the several views, A—A indicate railroad-ties of usual form and which may be of wood, concrete, cement, or other 55 material, B—B indicate railroad-rails also

of usual form and material, and C—C indicate my new fastening devices or clamps for fastening rails B firmly and rigidly to and upon ties A.

My new rail-clamp or fastening device C 60 includes two main coöperating members, which are identical in form and construction, being interchangeable duplicates. Each of these members, which may be cast or otherwise manufactured, and in the manufacture of which members the same pattern or mold may be employed for both, comprises preferably an integral rectangular cross-piece 1 and parallel end-pieces 2—2 disposed or depending obliquely downwardly from cross-piece 1 approximately at right angles thereto. Cross-piece 1 is flat on its under and inner side faces, as at 3 and 4, respectively, and has a thickness, especially at its inner side face 4, preferably 65 equal approximately to the thickness of the base-flange b of the rail B. Projecting laterally from the top or upper face of cross-piece 1 and disposed in the same general direction, or on the same side of cross-piece 1, with end-pieces 2—2, are lugs 5—5 adapted to engage at their under face with, and upon the upper face of, the base-flange b of the rail. End-pieces 2—2 are each cut away flush with the under face 3 of cross-piece 1 to provide faces 6—6 adapted to engage the rail B at the under face of its base-flange b. End-pieces 2—2 are also 70 obliquely cut away, as at 7—7, to provide shouldered extensions 8—8 transversely 75 perforated, as at 9, to receive a tie-engaging bolt 10 for securing or fastening the clamping-members to the tie A. Preferably 80 extensions 8—8 have a thickness equal approximately to half the thickness of end-pieces 2—2, and upper faces 8'—8' of extensions 8—8, while obliquely oppositely disposed to, have the same angle to the horizontal as, shoulders 7—7 of end-pieces 2—2, 85 extensions 8—8 of one member of the clamp 90 being adapted, when the clamping members are in operative position engaging the tie and rail, to flatwise smoothly engage and interlock at their faces 8'—8' with the shoulders 7—7 of the other member of the clamp. 95 100 In use or operation, the coöperating clamping members of my new rail-fastening device are adapted to straddle the tie A on opposite sides of the rail B with their cross-pieces 1 fitting smoothly at their under face 110

3 flatwise upon, and crosswise of, the upper face of the tie and at their inner face 4 flatwise against the outer edge of, with lugs 5 projecting laterally upon and thereby engaging with, the base-flange *b* of the rail, their end-pieces 2—2 not only snugly or closely at their inner faces hugging the tie at its opposite side faces, but also at their upper faces 6 flatwise engaging the rail on the under face of the base-flange *b* thereof. It will be seen, reference being had particularly to Fig. 1, that the end-pieces 2—2 of the clamping members abut or contact when operatively engaging the rail, the combined width of said end-pieces 2—2 at their flat faces 6 being equal approximately to the width of the base-flange *b* of the rail. The coöperating member of the clamp being in such operative position as described with the rail therebetween, their now oppositely-disposed extensions 8—8 interlock with their faces 8'—8' and said shoulders 7—7 in flatwise coöperative engagement and with their perforations 9 in register. The tie being suitably perforated, a securing-bolt 10 may be now readily passed transversely through the tie and said extensions, the clamping-members and rail being thereby firmly and rigidly fastened to the tie. The clamping-members with the rail engaged thereby being so fastened to the tie, it will at once be seen that the interlocking engagement of the extensions 8—8 of the clamping-members prevent any pivotal, tilting, or spreading movement thereof on bolt 10 which might tend to release the rail.

My new rail-fastening device is exceedingly simple in form and construction, may be easily and conveniently applied to, and operatively employed in connection with, the rail and tie, and, as will be seen, fulfills in every respect the object hereinbefore stated. It will further be seen that, shoulders 7—7 of each member of the clamp being disposed on the same relative side of its extensions 8—8, or, in other words, disposed toward the same end of cross-piece 1 thereof, the coöperating members of my new clamp may be interchangeably employed for engagement with the rail at either side thereof.

I am aware that minor changes in the form, construction, arrangement, and combination of the several parts of my new rail-fastening device may be made and substituted for those herein shown and described without departing from the nature and principle of my invention.

Having thus described my invention, what I claim and desire to secure by Letters Patent is:

1. A rail-fastening device comprising a pair of coöperating members each including a cross-piece having laterally projecting lugs on its upper face, end-pieces depending

from the cross-piece, and extensions on said end-pieces obliquely disposed to the cross-piece, each of said members being adapted to straddle the tie and to operatively engage the rail at the upper, side, and under faces of the base flange thereof, and a bolt adapted to engage with the tie and with said extensions for simultaneously fastening said members, and thereby the rail, to the tie. 79

2. A rail-fastening device comprising a pair of coöperating members each including a cross-piece having laterally projecting lugs on its upper face, end-pieces depending from the cross-piece, and extensions on said end-pieces obliquely disposed to the cross-piece, each of said members being adapted to straddle the tie and to operatively engage the rail at the upper, side, and under faces of the base-flange thereof, and a bolt adapted to engage with the tie and with said extensions for fastening said members, and thereby the rail, to the tie, said extensions being adapted to interlock to prevent pivotal movement of said members relatively to the rail when in engagement therewith. 85 93

3. A rail-fastening device comprising a pair of coöperating members each including a cross-piece having laterally projecting lugs on its upper face, end-pieces depending from the cross-piece, and shouldered extensions on said end-pieces obliquely disposed to the cross-piece, each of said members being adapted to straddle the tie and to operatively engage the rail at the upper, side, and under faces of the base-flange thereof, and a bolt adapted to engage with the tie and with said extensions for fastening said members, and thereby the rail, to the tie, the extensions of said members being adapted to overlap and interlock to prevent pivotal movement on said bolt of said members when in engagement with the rail. 95 100

4. A rail-fastening device comprising a pair of coöperating members each including a cross-piece and obliquely shouldered depending end-pieces, each of said members being adapted to straddle the tie and to operatively engage the rail at the upper, side, and under faces of the base-flange thereof, extensions on the end-pieces of said members, each of said extensions having a face obliquely oppositely disposed to, but having the same angle to the horizontal as, the shoulders of said end-pieces, and a bolt adapted to engage with the tie and with said extensions for fastening said members, and thereby the rail, to the tie, said extensions being adapted to interlockingly engage at their said faces with the shoulders of said end-pieces to prevent pivotal movement on said bolt of said members when in engagement with the rail. 115 120

5. A rail-fastening device comprising a pair of coöperating members each including a cross-piece, laterally projecting lugs 130

on the upper face of said cross-piece, and obliquely shouldered end-pieces depending from said cross-piece, each of said members being adapted to straddle the tie and to 5 operatively engage at its said cross-piece, lugs, and end-pieces with the rail at the side, upper, and end faces, respectively, of the base-flange thereof, extensions on the end pieces of said members, each of said extensions 10 having a face obliquely oppositely disposed to, but having the same angle to the horizontal as, the shoulders of said end-pieces, and a bolt adapted to engage with the tie and with said extensions for fastening 15 said members and thereby the rail to the tie, said extensions being adapted to interlockingly engage at their said faces with the shoulders of said end-pieces to prevent pivotal movement on said bolt of said end members when in engagement with the rail. 20

6. A rail-fastening device including a member adapted to straddle the tie and to operatively engage the rail at the upper, side, and under face of the base-flange there-

of, said member comprising a cross-piece, 25 laterally projecting lugs on the upper face of said cross-piece, end-pieces depending from said cross-piece, and extensions on said end-pieces obliquely disposed to said cross-piece, said extensions being adapted to receive means for fastening the member to the tie. 30

7. A rail-fastening device including a member adapted to straddle the tie and to operatively engage the rail at the upper, 35 side, and under faces of the base-flange thereof, said member comprising a cross-piece, laterally projecting lugs on the upper face of said cross-piece, end-pieces depending from said cross-piece, and extensions on 40 said end-pieces obliquely disposed to said cross-piece, said extensions being perforated to receive a bolt for fastening the member to the tie.

In testimony whereof, I have signed my 45 name to this specification.

FEKEĆS PÁL.
